FAN

Leslie Gant, Denver, Colo.

Application October 8, 1941, Serial No. 414,107

1 Claim. (Cl. 170—159)

This invention relates to air screws and fans of blade type, and has as an object to provide an improved and highly efficient construction and arrangement of blades in and for such devices.

A further object of the invention is to provide an improved fan designed to move relatively large volumes of air in proportion to the power required to actuate the fan.

A further object of the invention is to provide an improved fan blade susceptible of operative association with an axis of rotation to move relatively large volumes of air in proportion to the power input to the fan and along paths substantially parallel to the axis of blade rotation.

A further object of the invention is to provide an improved fan blade susceptible of rotation about an axis adjacent one of its ends to generate and maintain flow of engaged fluid along a substantially cylindrical path axially coincident with the axis of blade rotation.

A further object of the invention is to provide an improved fan blade susceptible of convenient manufacture from available material in units of relatively light weight.

A further object of the invention is to provide an improved fan blade adapted for either fixed or adjustable association with a hub in such number and specific arrangement as may be best suited to a given purpose or installation.

A further object of the invention is to provide an improved fan blade designed to entrap and efficiently redirect fluid disturbed by rotation thereof about an axis adjacent one end of the blade.

My invention consists in the construction, arrangement, and combination of elements hereinafter set forth, pointed out in my claim, and illustrated by the accompanying drawing, in which—

Figure 1 is an elevation of the output face of a four-blade fan constructed in accordance with the principles of my invention. Figure 2 is a perspective view of the construction and arrangement shown in Figure 1. Figure 3 is a side elevation, on an enlarged scale, of the construction and arrangement shown in Figure 1, certain of the elements being broken away to conserve space. Figure 4 is a fragmentary, detail section, on an enlarged scale, taken transversely of one of the improved fan blades on substantially the indicated line 4—4 of Figure 1.

The instant invention resides primarily in a novel fan blade construction and in the operative relationship of a plurality of identical such blades with an axis of rotation; the specific num-

ber and mounting of such blades in a given fan assembly being immaterial to the inventive concept residing in the blade.

In the construction of the improvement as shown, the numeral 10 designates a shaft whereof the longitudinal center line is the axis of rotation about which the improved blades are to revolve as a fan. The shaft 10 may be the driven shaft of a prime mover, such as an electric motor, internal-combustion engine, or the like, or said shaft may be independently mounted and supported for rotation deriving from such prime movers through suitable driving connections. A hub 11, conventionally illustrated, is fixed to and for rotation with the shaft 10 and carries a plurality of radial lugs 12, or equivalent means, in this instance shown as four in number, whereto the improved fan blades are secured at their inner ends in either fixed or adjustable relation with the hub, one such blade being mounted on each of the lugs 12.

The improved blades, regardless of their number or specific mounting in a given fan assembly, are identical and are uniformly spaced about and in identical relationship with the hub 11 and shaft 10. Each of said blades consists of a flat, relatively thin, smooth web 13 tapering from a narrower end adjacent the hub 11 to a wider end remote from said hub, and an integral, smooth flange portion 14 forming a somewhat obtuse angle with its associated web 13 and tapering from a wider end portion adjacent the narrower end of said web to substantially merge into the plane of said web at the wider end of the latter. The angle between the web 13 and flange 14 of each blade will be alike in all of the blades of a given fan assembly, but such angle may be varied somewhat to most efficiently meet the requirements of a given fan and a given speed of fan actuation, but in no event should such angle, within the contemplation of this invention, be less than ninety degrees.

The improved blades are fixed to the lugs 12, or otherwise mounted on the hub 11, so as to extend substantially radially from said hub with their wider web ends remote from the hub, with the planes of their webs 13 forming a small angle with a plane perpendicular to the shaft axis, and with the unflanged margin of each web 13 disposed as a leading edge in the direction of fan rotation. The leading edges of the webs 13 may be positioned radially of the shaft 10, but for enhanced efficiency it is preferred that the outer ends of the fan blades be moved axially of the shaft 10 to define a plane of rotation spaced from

the plane of rotation of their inner ends in the direction of their flanges 14, as is clearly shown in Figure 3. While the blades are shown as mounted and positioned by means of engagement of the inner ends of their flanges 14 in slots formed in the lugs 12 and pins or rivets extending through said lugs and the engaged flange portions, it is to be understood that such mounting means is in no sense limitative, but merely typical of any means for suitably engaging the 10 blades in operative relation with the hub 11.

With the web portions of the blades related to the hub in the manner shown and above described, the blade flanges 14 are disposed substantially radially of the shaft 10 in planes common to the shaft axis, and the flanged sides of the blades constitute the output side of the fan. Under certain operative conditions, it might prove desirable to dispose the wider ends of the webs 13 in trailing relation, in the direction of fan rotation, with their narrower inner ends, which is a modification within the contemplation of the invention, but such change would in no way alter the construction and operative principle of the improved blades nor vary the disposition of the blade webs and flanges relative to the air to be acted upon.

As will be apparent, the angular relationship between the web 13 and flange 14 of each blade is fixed at the time of blade construction, and any rotation of a mounted fan blade about an axis radially of the shaft 10 serves to simultaneously vary the pitch angle of the web 13 and the relation between the flange 14 and a plane radially of the shaft. When the blades are non-adjustably fixed to the hub 11, the free margins of the flanges 14 should not be advanced, in the direction of fan rotation, ahead of the junction of said flanges with their web portions, and when the blades are mounted for adjustment of their pitch angles, such adjustment should permit a maximum pitch angle of the webs 13 no greater than will dispose the flanges 14 in the radial planes of the shaft as above set forth.

When the shaft 10, carrying the improved fan blades constructed and arranged as shown and described, is rotated in the direction of the arrow in Figure 1, the leading, unflanged margins of the webs 13 cut into the air with little resistance and the flat faces of the webs, being disposed at an angle with the plane of rotation, tend to compress the air engaged thereby and initially urge such engaged air in a direction parallel to the shaft axis. Some of the air engaged by the inclined webs 13 is deflected forwardly, impinges against the corresponding flange 14, and is thence deflected again, in the manner shown by the arrows in Figure 4, to leave the blade with enhanced velocity in a direction substantially perpendicular to the plane of rotation. Some of the air engaged by the web 13 of a given blade is temporarily trapped and compressed in the angle between the web and associated flange 14, whence it escapes outwardly past and to some extent about the free margin of said flange in a stream of high velocity directed substantially perpendicular to the plane of blade rotation. The action of the flanges 14 has a fur-

ther advantageous effect in that the travel of said flanges, coupled with the flow of air outwardly across their leading faces, creates a suction effect immediately behind their trailing faces which operates to induce a flow of air through the fan and between the blades thereof, which induced air flow mingles with and amplifies the positively-generated currents from the directly-engaged blade elements. In similar manner, the rearward inclined faces of the webs 13 function to induce air flow into and between the fan blades, thereby perhaps initiating and certainly enhancing the induced flow past and behind the flanges 14.

In addition to air travel and reaction transversely of the fan blades, the mass of the engaged and compressed air reacts to the centrifugal forces developed through blade rotation to generate air flow longitudinally of and outwardly along the blade elements. Were the outer ends of the blades in the same plane of rotation with their inner ends, the centrifugally-induced air flow might be wasted in a jetting action past the blade tips, but when the blade outer ends are advanced relative to their inner ends, in the manner shown and described, the inclination of the blade web 13 acts on the longitudinally-moving air to deflect the flow forwardly and into the output stream from the fan, in much the manner indicated by the arrows in Figure 3. A further advantage is developed through advancing of the blade outer ends relative to their inner ends, in that the effective input area of the fan is thus given conical form with a consequent extent 35 greater than would obtain were such area a plane disc of corresponding diameter.

When used as an air-circulating fan or blower, the flanged output side of the blades is normally positioned to direct air away from the fan mounting and prime mover, while use of the fan for the propulsion of aircraft or boats normally requires a mounting such as will direct the air or fluid stream from the fan rearwardly of the craft to be moved.

Since many changes, variations and modifications in the specific form, construction, arrangement and combination of the elements shown and described may be had without departing from the spirit and principle of my invention, I wish to be understood as being limited solely by the scope of the appended claim, rather than by any details of the illustrative showing and foregoing description.

I claim as my invention:

In a fan of the character described, a blade formed with a tapered flat web portion longitudinally inclined at an angle to its axis of rotation and disposed with its wider end outermost to form an angle with its plane of rotation, and a triangular flange integral with the trailing edge of said web portion on the side of the latter forming an acute angle with the axis of rotation and disposed with its base adjacent the inner end of said web portion in such obtusely-angular relation with the plane of the latter as to position the flange substantially in a plane radial of the rotational axis.

LESLIE GANT.
